UNITED STATES PATENT OFFICE.

HENRY HORAN, OF EAST ORANGE, NEW JERSEY, ASSIGNOR TO THE LOWELL MANUFACTURING COMPANY, OF BOSTON, MASSACHUSETTS.

DESIGN FOR CARPET-BORDER, &c.

SPECIFICATION forming part of Design No. 23,485, dated July 17, 1894.

Application filed June 13, 1894. Serial No. 514,434. Term of patent 3½ years.

To all whom it may concern:

Be it known that I, HENRY HORAN, a citizen of the United States, residing at East Orange, in the county of Essex and State of New Jersey, have invented and produced a new and original Design for a Carpet-Border, of which the following is a specification, reference being had to the accompanying drawing, making a part of the same, which is sufficient to enable others skilled in the art to make and use my invention as a carpet-border.

What I claim as new, and desire to secure by Letters Patent, is—

The design for a carpet border, as shown in the accompanying drawing, and described in the specification.

HENRY HORAN.
